UNITED STATES PATENT OFFICE.

MARIA RÜTTGER-PELTI, OF LUCERNE, SWITZERLAND.

MASSAGING APPARATUS.

Application filed June 12, 1926, Serial No. 115,627, and in Switzerland July 6, 1925.

This invention relates to a massaging apparatus and consists in the provision of a casing mounted rotatably at the end of a handle and fitted on its face with a plurality 5 of projecting balls, means being provided for imparting rotation either to the casing relative to the handle or to the balls relative to the casing.

Fig. 1 of the accompanying drawings 10 represents a vertical section of the apparatus,

Fig. 2, a front view of the same, and

Fig. 3, a side view on an enlarged scale 15 of one of the ball supports.

The apparatus is composed of a circular 20 casing *a* which is rotatably mounted at the end of a handle *d*. The casing has a face plate *l* through apertures in which a plurality of balls *b* project so that they can be used by means of the handle for massaging 25 purposes. Each ball is held in a split, socketed member *c* which is supported at the back by a center screw *k* and which rests by means of a bevelled bearing surface in a correspondingly shaped aperture in the plate *l*. When the screws *k* are loosely applied to the 30 members *c*, the latter are capable of rotary motion, and when the screws are tightened up, the members become clamped to the face plate *l* and the balls to the members *c*. The latter are grooved like pulleys, and a belt *i* is situated about all the members for rotating the latter.

A driving shaft *e* is loosely fitted in the 35 handle *d* and receives motion, through the medium of a flexible shaft *m*, from any suitable hand, foot or power driven motor. One of the ball-supporting members is arranged in the center of the casing, coaxially with 40 the shaft *e*, and, instead of being supported by a screw *k*, is rotatably held by its base *h* in a recess in the bottom of the casing. This base has a square recess *n* adapted for engagement with a square head *g* at the end of 45 the shaft *e*. The shaft has a second square head *f* which, in the position shown in Fig. 1, engages a square slot in the casing *a* so that the latter is coupled to the shaft, the head *g* being out of engagement with the member *h*. When the shaft *e* is axially displaced in the handle so that the head *g* enters into engagement with the member *h*, the head *f* moves into a round portion of the casing slot so that the shaft becomes disengaged from the casing. By these means it is 50 possible to impart rotation either to the

casing itself, in which case the balls remain more or less stationary relative to the casing according to requirements, or to the balls, in which case the casing remains more or less stationary. In one instance a kneading effect and in the other instance a stroking effect is obtained, the magnitude of the treatment being modified by a regulation of the pressure and of the speed with which 65 the shaft is driven.

I claim:

1. A massaging apparatus comprising a handle, a casing supported rotatably at one end of said handle, balls held in said casing 70 so as to project through the front face thereof, means for imparting rotation either to the balls relative to the casing or to the casing relative to the handle, ball supports held rotatably in said casing, a gearing controlling said supports, and a driving shaft held rotatably and slidably in the handle, said shaft being formed with square heads which enable it by axial adjustment to be put into engagement either with the casing for rotating 75 the latter or with one of the ball supports for rotating the balls.

2. A massaging apparatus comprising a handle, a casing supported rotatably at one end of said handle, balls held in said casing 80 so as to project through the front face thereof, means for imparting rotation either to the balls relative to the casing or to the casing relative to the handle, split, socketed ball-supporting members, said members being 85 supported by means of their split and socketed parts and by means of bevelled bearing surfaces in apertures in the front face of the casing, center screws supporting the members from behind so that the members 90 and balls will either be held rotatably in the casing or clamped thereto by means of the screws, a gearing controlling the different members, a driving shaft held loosely in the handle, and means for coupling said 95 shaft either to the casing for rotating the latter or to one of said members for rotating the balls.

3. A massaging apparatus comprising a handle, a casing supported rotatably at one 105 end of said handle, balls held in said casing so as to project through the front face thereof, means for imparting rotation either to the balls relative to the casing or to the casing relative to the handle, split, socketed ball-supporting members, said members being supported by means of their split and 110

socketed parts and by means of beveled bearing surfaces in apertures in the front face of the casing, center screws supporting the members from behind so that the members and balls will either be held rotatably in the casing or clamped thereto by means of the screws, a belt carried sinuously about the members for driving the same, a driving

shaft held loosely in the handle, and means for coupling said shaft either to the casing 10 for rotating the latter or to one of said members for rotating the balls.

In testimony whereof I have signed my name to this specification.

FRAU MARIA RÜTTGER-PELLI.
